UNITED STATES PATENT OFFICE.

JAMES F. ROBERTS, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

ROTARY MACHINE.

Application filed June 8, 1925. Serial No. 35,517.

This invention relates in general to improvements in the construction of rotors, and relates more specifically to improvements in the construction and operation of the rotative elements of fluid propelling or propelled machines such as pumps or turbines.

An object of the invention is to provide improved rotor structure which is simple in construction and efficient in operation. Another object of the invention is to provide improved mechanism for controlling the operation of rotary machines. A further object of the invention is to provide an improved rotor especially applicable to machines which are operable at relatively high specific or characteristic speeds. Still another object of the invention is to provide efficient means for effecting angular adjustment of the vanes of a rotor either while the rotor is in motion or while it is at rest. Additional objects and advantages of the invention will be apparent in the course of the following description.

A clear conception of an embodiment of the invention and of the operation of devices constructed in accordance therewith, may be had by referring to the drawings accompanying and forming a part of this specification in which like reference characters designate the same or similar parts in the various views.

Fig. 1 is a central vertical section through the turbine casings and draft tube of a vertical hydraulic turbine installation.

Fig. 2 is an enlarged fragmentary sectional view through a turbine rotor the section being taken horizontally in the plane of the vane pivot axes.

Fig. 3 is an enlarged fragmentary sectional view through the turbine rotor, the section being taken along the irregular line III-III of Fig. 2.

Fig. 4 is an enlarged fragmentary vertical section through a portion of the adjusting mechanism associated with the main shaft.

Fig. 5 is an enlarged fragmentary horizontal section through a portion of the adjusting mechanism and through the main shaft.

While the invention is specifically shown and described herein as being applied to a hydraulic turbine rotor, it will be apparent that at least some of the features of the improvement are more generally applicable to rotors of any kind. The hydraulic turbine

specifically illustrated, comprises in general a rotor 2 having a plurality of vanes 3 radiating from a central hub 4 which is secured to a hollow main shaft 5; a main casing 6 for conducting water to the rotor 2 and for changing the direction of flow of the water from radial to axial; and a draft tube 11 for conducting the water from the rotor 2 to the tailrace in a well known manner.

The dove-tail shaped radiating vanes 3 of the rotor 2 are pivotally associated with the hub 4, the inner end of each vane 3 being provided with bearing portions 39, 41, 40 which are journaled in the hub 4. The hub 4 is formed of upper and lower sections detachably connected by bolts 38, the hub being split in the horizontal plane of the vane pivots. Each of the vanes has a worm wheel 34 formed integral with its inner pivotal end, the hub sections being recessed to permit free rotation of the worm wheel 34 therein. Laterally adjacent to the inner end of each of the vane pivots, and mounted within the sections of the hub 4, is a vertical pinion shaft 36 the medial portion of which carries a worm 37 meshing with an adjacent worm wheel 34, and the lower extremity of each of which has a pinion 35 secured thereto. The pinions 35 mesh with gears 33 supported upon stub-shafts 43, and the gears 33 in turn mesh with a pinion 42 formed integral with the lower extremity of the actuating shaft 24. The spur gears 33, 35, 42 are located beneath the hub 4 and are normally enclosed by means of a removable cap 10 secured to the hub 4. The vertical actuating shaft 24 extends upwardly through the hollow main shaft 5 and has a gear 32 formed integral with the upper extremity thereof. The lower extremity of the hollow main shaft 5 may be provided with a flange 15 to which the hub 4 is secured by means of bolts.

The mechanism for effecting adjustment of the vanes 3 about their pivots, comprises a cross shaft 25 carried in bearings in the main shaft 5 and in a bracket 44 secured to the main shaft, the shaft 25 having a worm 31 formed integral therewith and meshing with the gear 32 of the actuating shaft 24. The outer extremity of the cross shaft 25 carries a bevel pinion 28 which meshes with upper and lower bevel gears 29, 30, respectively. The upper bevel gear 29 is formed integral with the upper drum 18 which is

rotatably supported upon the hollow main shaft 5 and is prevented from moving longitudinally of the shaft 5 by means of an upper collar 45. The lower bevel gear 30 is formed integral with a lower drum 19 which is rotatable about the hollow main shaft 5 and is prevented from moving longitudinally of the main shaft by means of a lower collar 46. Coacting with the drums 18, 19 are 10 brake bands 20, 21 corresponding ends of which are rigidly attached to a stationary bracket and the oppositely corresponding ends of which are connected with an adjusting lever 16 mounted upon a pivot 22 as 15 shown in Fig. 1. The medial portion of the cross shaft 25 carries a worm 26 which meshes with a worm wheel 27 formed integral with the lower end of the indicating spindle 23. The spindle 23 is supported in a bearing in 20 the main shaft 5 and has a threaded upper end coacting with screw threads in a vertically slidable indicator 17. The indicator 17 is slidably supported by the main shaft 5 and may be caused to cooperate with a gage 25 whereby the angular disposition of the vanes 3 may be readily observed from the exterior 30 of the turbine casing by looking at the indicator 17.

The hollow main shaft 5 which supports 30 the rotor 2 is mounted in suitable bearings in the main casing 6 which is rigidly supported from a foundation 13 by means of supporting rods or stay bolts 14. An annular series 35 of pivotally supported adjustable guide vanes 7 are adapted to control the admission of water to a vane free transition space 8, the guide vanes 7 being adjustable by means of an adjusting ring 9 in a well known manner. Within the transition space 8 is located a 40 guide wall 12 which is adapted to change the direction of flow of the water admitted to the chamber 8 from radial to axial.

During normal operation of the turbine, 45 the adjusting lever 16 is disposed in neutral position as shown in Fig. 1 and, water is admitted past the guide vanes 7, through the transition space 8 to the rotor 2, and is discharged from the rotor 2 into the draft tube 11. The quantity of water thus admitted 50 may be controlled in a well known manner by adjustment of the guide vanes 7 about their supporting pivots by manipulation of the ring 9, and the water passes through the rotor 2 in the form of a swirling mass or 55 vortex. This vortex of liquid cooperates with the rotor vanes 3 to produce rotation of the hollow main shaft 5 and the elements carried thereby, the brake bands 20, 21 loosely surrounding the drums 18, 19 during such 60 normal operation of the unit.

If it is desired to effect angular adjustment of the vanes 3 about their pivotal axes, it is unnecessary to interfere with the flow of water through the rotor. If the adjusting lever 16 is shifted either up or down from

neutral position, one or the other of the brake bands 20, 21 will become effective to grip the drum 18 or 19 embraced thereby and will prevent rotation of the gripped drum with the shaft 5. The bevel pinion 28 will immediately roll upon the stationarily held bevel gear 29 or 30 and will produce rotation of the cross shaft 25 and of the worms 26, 31 carried thereby. The rotation of the worm 26 will be transmitted through the spindle 23 to the indicator 17 causing the indicator to slowly travel either up or down along the shaft 5, depending upon which brake is effective. The rotation of the worm 31 will be transmitted through the actuating shaft 24 to the gears 33 and from thence through the gears 35 and the shafts 36 to the worm wheels 34 associated with the pivotal ends of the vanes 3, thereby causing the vanes 3 to slowly revolve upon their own axes in the desired direction. It will be obvious that motion of the lever 16 in one direction will produce corresponding rotation of all of the vanes 3 about their own axes in corresponding directions, and that opposite movement of the lever 16 will produce opposite simultaneous rotation of the vanes 3 about their pivotal axes. If the lever 16 is brought back to neutral position, the motion of the vanes 3 and of the indicator 17 automatically ceases and the vanes 3 as well as the indicator 17 are locked in adjusted position by virtue of the worm gearing associated with these elements. It will thus be noted that the angular disposition of the vanes 3 of the rotor 2 may be altered at will from the exterior of the turbine casing, to produce operation of the turbine at maximum efficiency.

The various gears are readily accessible for inspection. By removing the hub cap 10, access is had to the gears 24, 33, 35 located below the hub 4. By removing the clamping bolts 38, the vane pivots and the gearing within the hub 4 are readily accessible. The actuating shaft 24 may be readily endwise removed from within the main shaft 5 by virtue of the fact that the gears 32, 42 are of diameters not greater than that of the shaft 24, and this actuating shaft may be normally retained within the shaft 5 in any convenient manner. The transverse shaft 25 may be readily removed by removal of the bracket 44 and the bevel gears 29, 30 are likewise removable from the shaft 5 upon removal of the retaining collars 45, 46. By forming and disposing the gears 29, 30, 28 as shown in Figs. 4 and 5, undesirable projections on the rotating shaft 5 are avoided thus eliminating danger of injuring attendants.

It should be understood that it is not desired to limit the invention to the exact details of construction and operation herein shown and described for various modifications within the scope of the claims may

occur to persons skilled in the art.

It is claimed and desired to secure by Letters Patent:

1. In combination, a hollow main shaft, 5 a hub secured to an end of said shaft, a plurality of vanes radiating from the axis of said main shaft and pivotally supported by said hub, worm gearing associated with each of said vanes adjacent to its pivot, an adjusting shaft located within and concentrically of said main shaft, motion transmitting mechanism connecting said adjusting shaft and said worm gearing, and means associated with said main shaft remote from said hub for relatively rotating said main and said adjusting shafts.

2. In combination, a hollow main shaft, a hub secured to said shaft, a vane pivotally supported by said hub, worm gearing associated with said vane adjacent to its pivot, an adjusting shaft located within said main shaft and extending through said hub, and spur gearing connecting said adjusting shaft and said worm gearing at the side of said hub remote from said hollow shaft.

3. In combination, a hollow main shaft, a hub secured to an end of said shaft, a plurality of vanes radiating from the axis of said main shaft and pivotally supported by 30 said hub, worm gearing associated with each of said vanes adjacent to its pivot, an adjusting shaft located within said main shaft and extending through said hub, spur gearing connecting said adjusting shaft and said worm gearing at the side of said hub remote from said hollow shaft, and means associated with said main shaft on the opposite side of said hub for relatively rotating said main and said adjusting shafts to vary the 35 angularity of said vanes about their pivots.

4. In combination, a hollow main shaft, a hub secured to an end of said shaft, a plurality of vanes pivotally supported by said hub, means associated with each of said vanes 45 adjacent to its pivot for rotating said vanes about their pivotal axes, an adjusting shaft located within said main shaft and extending beyond the end of said hub remote from said main shaft, gearing connecting said vane rotating means and the portion of said adjusting shaft which extends beyond said hub, and means associated with a medial portion of said main shaft for relatively rotating said shafts to effect simultaneous adjustment 55 of all of said vanes about their pivotal axes.

5. In combination, a pair of concentrically disposed shafts, a plurality of vanes, pivotally associated with said shafts, motion transmitting mechanism connecting one of 60 said shafts and said vanes, a pair of laterally spaced gears carried by one of said shafts, a pinion coacting with both of said

gears, motion transmitting mechanism connecting said pinion and the other of said shafts, and means for retarding the rotary motion of one of said gears to produce relative rotation between said shafts to vary the angularity of said vanes about their pivotal axes. 65

6. In combination, a hollow main shaft, 70 an auxiliary shaft disposed centrally within said main shaft, a plurality of vanes pivotally associated with one of said shafts, motion transmitting mechanism connecting one of said shafts and said vanes, a pair of laterally spaced gears carried by said main shaft, a pinion cooperating with said gears, mechanism connecting said pinion and said auxiliary shaft, and means for retarding the rotary motion of one of said gears while 80 permitting rotation of the other with said main shaft to cause relative rotation of said shafts to vary the angularity of said vanes about their pivotal axes. 85

7. In combination, a main shaft, a plurality of vanes pivotally associated with said shaft, mechanism associated with said main shaft intermediate its ends for adjusting said vanes about their pivotal axes, and means associated with said main shaft and 90 movable relatively thereto to indicate the position of adjustment of said vanes. 95

8. In combination, a hollow main shaft, a plurality of vanes pivotally associated with said main shaft, an auxiliary shaft disposed within said main shaft, motion transmitting mechanism connecting said auxiliary shaft and said vanes, means for relatively rotating said main and said auxiliary shafts to vary the angularity of said vanes about their 100 pivotal axes, and means associated with said main shaft and movable relatively thereto to indicate the position of adjustment of said vanes about their axes. 105

9. In combination, a main shaft, a hub associated with said shaft, a plurality of vanes pivotally associated with said hub, mechanism for adjusting said vanes about their pivotal axes, and means associated with said main shaft and movable relatively 110 thereto to indicate the position of adjustment of said vanes. 115

10. In combination, a main shaft, a hub associated with an end of said shaft, a plurality of vanes pivotally associated with said hub, mechanism for adjusting said vanes about their pivotal axes, and means associated with said main shaft remote from said hub and movable relatively thereto to indicate the position of adjustment of said 120 vanes.

In testimony whereof, the signature of the inventor is affixed hereto.

JAMES F. ROBERTS.
